D. J. MCGILL.
FENCE POST.
APPLICATION FILED NOV. 18, 1912.

Patented May 6, 1913.

UNITED STATES PATENT OFFICE.

DANIEL J. MCGILL, OF DAVISON, MICHIGAN.

FENCE-POST.

1,061,097

Specification of Letters Patent.

Patented May 6, 1913.

Application filed November 18, 1912. Serial No. 732,067.

To all whom it may concern:

Be it known that I, DANIEL J. MCGILL, a citizen of the United States of America, residing at Davison, in the county of Genesee and State of Michigan, have invented certain new and useful Improvements in Fence-Posts, of which the following is a specification, reference being had therein to the accompanying drawing.

10 This invention relates to fence posts, and has special reference to the fence post consisting of two sections, one of which may be readily applied to the other so that repairs may be quickly made and so that the height 15 of the fence may be increased at any time if desired.

The principal object of the invention is to improve and simplify the general construction of devices of this character.

20 Another object of the invention is to provide a fence post having a novel form of base member and detachable upper member.

With the above and other objects in view, the invention consists in general of certain 25 novel details of construction and combinations of parts hereinafter fully described, illustrated in the accompanying drawings, and specifically claimed.

In the accompanying drawings, like characters of reference indicate like parts in the several views, and:—Figure 1 is a side elevation of the fence showing the improved posts in use therewith. Fig. 2 is a transverse section through such a fence. Fig. 3 is a vertical section through one of the posts. Fig. 4 is a section on the line 4—4 of Fig. 2. Fig. 5 is a section on the line 5—5 of Fig. 3.

In carrying out the objects of this invention there is provided a concrete base 10 40 wherein is embedded an angle bar 11 which passes through a ring 12 adjacent the top of the base 10 and similarly embedded in the concrete. The parts just described form what may be termed the lower portion of 45 the post and to these parts is secured the upper portion of the post which consists of a body 13 formed of angle iron having a cover plate 14 formed of strap iron and provided at its lower end with an offset portion 50 15 for the accommodation of the upper part of the angle 11. These upper and lower

portions are secured together by means of bolts 16 and nuts 17, and the cover plate is likewise secured to the body 13 by bolts 18 and nuts 19 so that the line wires 20 may be 55 clamped between the cover plate and the body 13. In order to reinforce the concrete longitudinally, rods 21 are also employed which extend upward through the ring 12, the rods being located adjacent each corner 60 the cement portion of the post. By means of this construction the fence may be stretched as a whole and the cover plates of the different posts clamped tightly to the body, thus preventing movement of the 65 wires. Furthermore by removing the bolts 16 a different height of upper member may be suspended, or if necessary, these portions may be removed for repairs or replacement. Also, reinforcing rings at the top of the post 70 prevent breaking of the concrete around the top.

There has thus been provided a simple and efficient device of the kind described and for the purpose specified. 75

Having thus described the invention, what is claimed is:—

In a device of the class described, the combination with a plurality of strands, a fence post comprising a concrete base, an angle iron extending into said base and projecting thereabove, a second angle iron fixed upon the first angle iron, a cover plate extending along the side of said second angle iron and provided with an offset portion extending 80 over one flange of the first angle iron, means securing said first angle iron to said second angle iron, means for holding said cover plate to said second angle iron, said plate adapted to engage said strands of wire for 85 holding the same upon the second angle iron, said offset portion adapted to engage said strands for holding the same, whereby the strands may be placed so as to rest upon the top portion of the base of the post and 90 to be clamped thereon by said offset portion.

In testimony whereof I hereunto affix my signature in presence of two witnesses.

DANIEL J. MCGILL.
